UNITED STATES PATENT OFFICE.

KNOTT H. PEDRICK, OF HUDSON, MASSACHUSETTS, ASSIGNOR OF ONE-HALF
TO CYRUS D. MUNSON, OF SAME PLACE.

ENVELOPE.

SPECIFICATION forming part of Letters Patent No. 256,241, dated April 11, 1882.

Application filed October 18, 1881. (No model.)

To all whom it may concern:

Be it known that I, KNOTT H. PEDRICK, of Hudson, in the county of Middlesex and State of Massachusetts, have invented certain new and useful Improvements in Envelopes; and I do hereby declare the following to be a full, clear, and exact description of the same, reference being had to the accompanying drawings, forming a part of this specification, in which—

10 Figure 1 is a plan view of the blank from which the envelope is made. Fig. 2 is a perspective view, showing the blank creased and ready to be joined to form an open envelope. Fig. 3 is a plan view of the envelope closed, 15 looking from the flap side and showing the printed matter on the flap.

Similar letters of reference in the several figures denote the same parts.

My invention has for its object to provide 20 an improved envelope which, when closed, shall present a smooth, unbroken surface on each side, and which shall be of uniform thickness, except within a short distance of its side and top edges, so as to enable a clear and 25 regular impression to be made on either side by a printing-press.

To this end my invention consists of an envelope consisting of a middle portion having short end flaps which are adapted to be 30 folded inward, and are provided with adhesive material on their outer faces, an inner flap adapted to be folded down upon the inner portion so as to cover the entire face of the same except for a short distance from the 35 top and to be pasted to the end flaps, and an upper outer flap adapted to be folded down upon the inner flap so as to cover the same and extend flush with the edges of the middle portion.

40 In the accompanying drawings, A represents the middle portion of the envelope, provided at its end with short flaps *a a*, which are folded inward, as shown in Fig. 3, and have paste or other adhesive material applied 45 on their outer faces, as indicated by the lines *a' a'* in Fig. 2.

B is the first or inner flap, folded inward against the middle portion, A, and made to

adhere to the pasted end flaps, *a a*, and having a portion cut away at *e* to facilitate the opening of the envelope by the thumb or finger. 50

C is the outer flap, which folds down over the inner flap, B, completely covering the same and extending flush with the end and bottom edges of the portion A, as shown in Fig. 3. 55

From this construction it will be seen that that part of the envelope included within the space bounded by the dotted lines shown in Fig. 3 is composed of three plies of paper, of uniform thickness throughout, and that when 60 either face of the closed envelope is printed upon within said inclosed space the impression will be clear, smooth, and regular, and not broken and irregular, as it would be if the number of thicknesses of material varied within 65 said space, as it does in an envelope as ordinarily constructed. I am therefore enabled to entirely fill the space with clear and regular printed matter, impressed upon one or both sides of the envelope, and I am also enabled 70 to write upon one or both sides of the envelope and have an even and regular surface for the pen to act upon.

I claim as my invention—

The herein-described envelope, consisting of 75 the middle portion, A, having the short end flaps, *a a*, which are folded inward and provided with adhesive material on their outer faces, an inner flap, B, having the cut-away portion *e*, and folded down upon the middle portion, 80 A, so as to cover nearly the entire face of the same, and secured to the end flaps, and an outer flap, C, folded down upon the inner flap and extending flush with the edges of the inner portion, A, the said construction producing 85 an article having three unbroken plies of uniform thickness, except where the side flaps and cut-away portion *e* are located, and affording a smooth, unbroken body of uniform thickness, upon either side of which a clear and 90 regular impression can be made by a printing-press, as set forth.

KNOTT H. PEDRICK.
